BUFFER FOR LOOM BOBBIN RECEIVERS

Richard G. Turner, Worcester, Mass., assignor to
Crompton & Knowles Loom Works, Worcester,
Mass., a corporation of Massachusetts

Application October 26, 1943, Serial No. 507,933

8 Claims. (Cl. 130—255)

This invention relates to improvements in weft replenishing looms and it is the general object of the invention to provide an improved bobbin buffer for bobbin cans or receivers.

In weft replenishing looms it is common practice to employ a bobbin can in front of the lay at the magazine end of the loom to receive the depleted bobbins which are expelled from the shuttle during weft replenishing operations. When the bobbins are made with thin metallic ferrules such as are customarily used with electric weft detectors the shock of the discharge is likely to dent the ferrules and it is a further object of my present invention to provide a simple form of buffer readily attachable to a bobbin receiver and located in the path of the expelled bobbin to direct its path and prevent it from striking other bobbins in the receiver with sufficient force to injure them.

Bobbins for weft replenishing looms are customarily made with a head or butt surrounded with three hardened steel rings by means of which the bobbin is held in the spring jaws of the shuttle. These rings project beyond the periphery of the bobbin butt and are sufficiently hard to damage bobbin barrels and ferrules on the barrels, as by denting, thus rendering the bobbins of little value for further use with fine weft or with electric weft detectors. The rings and butt constitute a heavy part of the bobbin and are projected downwardly with considerable force by the transerrer hammer at the time of replenishing operation. It is a further object of my invention to provide a buffer having a yielding part lying in the path of the outgoing bobbin butt to engage and retard the latter and also deflect it toward a part of the bobbin can, thereby checking its force, before the bobbin falls on the other bobbins in the can. In this way damaging contact between the rings of the outgoing bobbin and the bobbins already in the can is avoided.

It is a more particular object of my present invention to provide a bobbin buffer having a body grooved to fit over the beaded edge of a bobbin can and provided with a strip of resilient material, such as leather, which can yield upon impact with the outgoing bobbin. The buffer can conveniently be made of wood and the groove made in such a way as to fit easily over an upper edge of the can and at the same time prevent accidental lateral or upward displacement thereof.

Bobbin cans are usually made of resilient sheet material and it is another object of my present

invention to make use of this property of the can material to absorb energy from the descending bobbin. The buffer to be described hereinafter is supported on a wall of the can which is deflected somewhat upon initial contact between the descending bobbin and the buffer, thereby moving the latter as a whole and permitting its inertia to retard the descending bobbin.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a side elevation of a portion of a weft replenishing loom showing a bobbin can provided with my present invention;

Fig. 2 is a rear elevation of the bobbin can looking in the direction of arrow 2, Fig. 1, showing the location of my improved buffer;

Fig. 3 is an enlarged vertical section on line 3—3 of Fig. 2 showing the resilient part of the buffer in normal and deflected positions and also setting forth the relationship between the buffer and the beaded edge of the can,

Fig. 4 is a perspective view of the improved buffer;

Figs. 5 and 6 are diagrammatic views showing the manner in which the buffer can be readily attached to and detached from the bobbin can,

Fig. 7 is an end view of the buffer on an enlarged scale looking in the direction of arrow 7, Fig. 2,

Fig. 8 shows a bobbin which may be used in a loom provided with my invention, and

Fig. 9 is a detailed front elevation of the lay carried chute and the relation which it sustains to my improved buffer, looking in the direction of arrow 8, Fig. 1.

Referring particularly to Fig. 1, I have shown a weft replenishing loom 10 having a reserve bobbin magazine M provided with a transerrer arm 11 operated in the usual manner to insert a fresh or reserve bobbin B into a shuttle S in the shuttle box 12 on the lay L under the magazine. The shuttle contains a bobbin B' which in the present instance may be assumed to be depleted or exhausted of weft. A bobbin chute 13 is secured to the lay under box 12 and projects downwardly and forwardly toward a bobbin can C which is preferably supported on a stand 14 secured in any approved manner to the loom frame. The can may be made of any approved material, such as inherently resilient sheet metal,

and has an open top surrounded by a bead 15 which may be in the form of a wire or rod around which the upper edge of the sheet metal is wrapped or rolled. The can has outer and inner side walls 16 and 17, respectively, and has a front wall 18 the upper end of which is formed with a rolled hand hold 20. As shown in Fig. 2 rear wall 21 of the can has a relatively high section 22 at the left and the lower section 23 at the right. The bead 15 extends around recess 24 formed in the rear wall 21 between section 22 and inner wall 17, and has a vertical part 25 at the left of recess 24 as viewed in Fig. 2. The bead may also extend upwardly as at 26 on the right side of Fig. 2 along the rear edge of wall 17.

The bobbin B may be of any form adaptable for use in bobbin changing looms, but in Fig. 8 I show a form commonly used in certain types of looms. The bobbin B', illustrated for convenience, has a head 30 surrounded by metal rings 31 to be held by spring clips not shown in the shuttle S. The bobbin is also provided with a barrel 32 a portion of which adjacent the head 30 is surrounded with a metallic ferrule 33. The ferrule is preferably made of thin sheet metal and cooperates with a weft detector D of the electrical type see Fig. 1. When the ferrule is empty the detector D indicates weft exhaustion in well-known manner to cause downward movement of the transfer arm, at which time bobbin B is inserted into the shuttle and bobbin B' is forced downwardly through a slot 35 in the lay along the bobbin chute 13 toward the can. This operation occurs when the lay is on front center position and the chute is adjacent the rear part of the can adjacent to or located in recess 24. As seen in Fig. 9, the chute 12 may have a lateral forwardly extending wall 36 and a rib 37, these last named parts being so located as to direct the butt 30 of the bobbin along its downward path toward the can. The bobbin is generally made of wood or paper which is soft enough to be damaged if struck a hard blow by rings 31.

The foregoing is of common construction and except as indicated hereinafter forms no part of my present invention. The bobbins which descend into the can C accumulate at the bottom thereof and if the rings 31 of a bobbin being expelled from the shuttle should strike a ferrule 33 or soft part of bobbin in the can damage of such extent might result as would present an imperfect surface to the weft or detector D and thereby interfere with the correct operation of the loom. It is the general purpose of my invention to provide a buffer which will prevent this damaging engagement between the rings 31 and the bobbins in the can.

In carrying my present invention into effect I provide a buffer substantially as shown in Fig. 4 having an elongated body 40 provided with a forwardly extending support 41, the upper surface 42 of which extends downwardly and forwardly. Support 41 has a substantially horizontal bottom surface 43 and a notch 44 cut in the top thereof for the reception of the upper rear end of a buffer strip 45 of resilient material tacked or otherwise secured to support 41. The rear and bottom end of strip 45 extends under the surface 43 and is secured to the bottom of the support 41. The buffer 45 may be made of leather or other material which will yield somewhat under the impact of the outgoing bobbin. The upper surface of the buffer is inclined generally in a downwardly and forwardly extending direction so

that a bobbin would be deflected from it toward the front wall 18 of the bobbin can.

The elongated body 40 is provided with a groove designated generally at 50 to receive the bead 15 extending along the bottom of the recess 24 between parts 25 and 26 of the bead. This groove is defined in part by top and rear walls 51 and 52, respectively, on the latter of which is formed a bottom forwardly projecting rib 53. A second rib 54 extends rearwardly from the front wall 55 of slot 50 on body 40. The upper part 56 of the groove 50 above rib 53, below wall 51, and between the walls 52 and 55 is so proportioned as to receive the bead 15.

When assembling the buffer on the bobbin can the procedure may be that suggested in Figs. 5, 6 and 3. Fig. 5 suggests that the buffer may be inclined upwardly and forwardly so that the bead 15 will pass between the rib 53 and wall 55. The buffer is then inclined downwardly somewhat so that the bead 15 can slip into the upper end 56 of the groove, see Fig. 6, after which the buffer is released and falls by its own weight to the position shown in Fig. 3. The walls 51 and 52, and rib 53, prevent accidental downward, forward, and upward displacements of the buffer, respectively. The weight of the buffer tends to resist its rearward displacement, and holds wall 52 against bead 15 and rib 54 against the front of rear can wall 21. The buffer is thus held in operating position on the bobbin can.

In operation, the buffer will normally be in the position and form shown in Fig. 1 and full lines in Fig. 3 with the rib 54 resting against the rear wall 21 of the can C. The buffer 45 will be in the path of the descending bobbin in such a position as to be struck by the butt 30. When the bobbin strikes the resilient buffer strip 45 there will be a slight angular movement of the whole buffer in a counter-clockwise direction as viewed in Fig. 1 due to the resilience of rear wall 21. There is thus provided an initial absorption of the energy stored in the descending bobbin due to the inertia of the buffer as a whole. The backward bowing of wall 21 is indicated in dotted lines in Fig. 3. Exertion of further force by the bobbin against strip 45 bends the latter from the full to the dotted line position shown in Fig. 3, after which the bobbin is deflected forwardly against the front wall 18 of the can. The bobbin then falls by its own weight to the bottom of the can or on any bobbins which may have accumulated in the can from previous replenishing operation without damaging these bobbins. When it is desired to remove the buffer from the can it is lifted, pushed rearwardly, and then given a further upward movement in a procedure which is substantially the reverse of that followed when the buffer is applied to the can.

From the foregoing it will be seen that I have provided a simple form of buffer readily adaptable to the rear edge of a bobbin can and having a strip of resilient material, such as the leather 45, lying in the path of the bobbin to retard movement of the latter and permit the bobbin to fall easily into the can without damaging other bobbins in the can. The body 40 is of sufficient length to be held more or less in correct lengthwise position with respect to the lay by the vertical parts 25 and 26 of the bead 15. The buffer is so constructed that the greater part of its weight lies forwardly of the supporting bead 15, and this fact together with the shape of the groove 50 tends to hold the buffer in correct position during loom operation. When the leather

strip 45 is relatively thick and offers considerable resistance to bending or deflection it may bend to approximately the dotted line position indicated in Fig. 3, but if the leather strip is relatively flexible it may be bent down to engage the inclined surface 42 of the support 41. It will also be seen that because of the resilience of the wall 21 of the can the energy of the descending bobbin is absorbed in two stages the first of which is accompanied by a movement of the entire buffer unit and the second of which is accompanied by a deflection of the buffer strip 45 from the full to the dotted line position shown in Fig. 3. The material of which the bobbin can is made therefore contributes partly to the action of the buffer in absorbing energy stored in the descending bobbin and permits the inertia of the buffer unit to retard motion of the buffer.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom having a bobbin can to receive bobbins discharged from the loom during a weft replenishing operation, said can having an upper beaded edge, a bobbin buffer comprising a body having walls thereon defining a groove provided with an undercut to receive the beaded edge of the can to prevent accidental upward displacement of the buffer, and a resilient buffer member having portions thereof secured to said body and having other portions spaced from said body and lying in the path of a bobbin discharged from the loom toward the can to retard movement of the bobbin.

2. In a weft replenishing loom having provision for directing an empty bobbin toward a bobbin can having a bead around an upper edge thereof, a bobbin buffer including a body having a longitudinal slot therein and having a rib on the lower part of the body below said slot for engagement with the can, the slot having a lateral offset on the side of the slot opposite said rib to receive said bead, and a resilient member fastened to the body and having a portion lying in the path of the discharged bobbin to retard movement thereof.

3. In a weft replenishing loom having provision for discharging an empty bobbin toward a bobbin can the rear wall of which has a rearwardly extending bead, a buffer body provided with a longitudinal groove having an offset to receive said bead, said body having a portion thereof below said offset engaging said rear wall and said body extending into the can so that the weight thereof tends to hold said offset around said bead, and a buffer member on said body lying

in the path of the discharged bobbin to retard movement of the latter.

4. In a weft replenishing loom having provision for discharging an empty bobbin toward a bobbin can, said can having a resilient wall, a buffer member supported on said wall in the path of a discharged bobbin, and a resilient member on said buffer positioned for engagement with the discharged bobbin, said wall holding said buffer and resilient member in normal position but yielding due to the resilience thereof upon impact of a discharged bobbin with said resilient member, and said resilient member thereafter yielding, the resilient yielding of said wall and of said resilient member both acting to retard the bobbin.

5. In a weft replenishing loom having provision for discharging an empty bobbin into a bobbin can, said can having a resilient wall, a buffer mounted on said wall and having a body, and a resilient member on said body lying in the path of a discharged bobbin, a discharged bobbin upon impact with the resilient member having the motion thereof subjected to an initial retardation due to deflection of said wall by a force transmitted from the bobbin through the body and said bobbin being subject to a second retardation due to yielding of said resilient member.

6. In a weft replenishing loom having provision for discharging an empty bobbin toward a bobbin can, said can having a resilient rear wall lying in a plane transverse of the path traversed by the discharged bobbin, a buffer having a weighted body supported on said wall and a resilient member on said body, retardation of a discharged bobbin striking said member being due to two factors, one of which is the inertia of said body when the latter moves due to resilience of said wall and the other is the resilience of said member.

7. A bobbin buffer for the discharged bobbin of a weft replenishing loom having a supporting member, said buffer comprising an elongated body having a slot along the rear part thereof to receive said supporting member, and a strip of resilient material secured to said body and extending forwardly therefrom in spaced relation thereto for engagement with a discharged bobbin.

8. A bobbin buffer for the discharged bobbin of a weft replenishing loom having a supporting member, said buffer comprising a body having an elongated slot therein to receive said supporting member, a projection extending forwardly from said body and having a downwardly and forwardly inclined surface, and a strip of resilient material secured to said body and extending forwardly, in front of and under said projection and spaced from said inclined surface.

RICHARD G. TURNER.
